UNITED STATES PATENT OFFICE.

AUSTIN L. WERTZ, OF LAKEWOOD, OHIO.

PUMP.

Application filed March 21, 1927. Serial No. 176,919.

This invention relates to measuring and dispensing pumps particularly adapted for use in dispensing lubricating oil at automobile filling stations.

5 One of the objects of the invention is to provide a dispensing pump of the character described which comprises comparatively few parts, is easily assembled and disassembled for the purpose of repairing or 10 replacing worn parts, and which is adapted for quantity production at comparatively low cost.

Another object of the invention is to provide a pump of the type referred to in 15 which the pump head is cast in one piece and is provided with an integral inwardly projecting portion on one side thereof having a vertically extending opening therein through which extends the piston rack and 20 which is provided with a horizontally extending bore or passageway communicating with the opening at its inner end and in which is journaled the pinion for actuating the rack, the projecting portion constituting a guide for the rack as well as a bearing 25 for the pinion.

Further and more limited objects of the invention will appear as the description proceeds and by reference to the accompanying drawing in which Fig. 1 is a vertical sectional view of a pump constructed in accordance with my invention; Fig. 2 is a horizontal sectional view on the line 2—2 of Fig. 1 and Fig. 3 is a horizontal sectional view on the line 3—3 of Fig. 1.

Referring now to the drawings the numeral 1 designates the pump base, 2 the pump cylinder and 3 the pump head which is shaped as shown most clearly in Fig. 1 40 and provided with a discharge pipe 4 leading outwardly therefrom. The base member 1 is somewhat conical in shape and arranged therein is a check valve 5 which is held in place by a plate 6 detachably secured to the base member by a screw 7. Arranged within the pump cylinder 2 is a piston 8 having an opening 9 therein adjacent one side. Arranged over the opening 9 is a check valve 10 which is secured to the 45 piston by means of a plate 11 which is detachably secured to the piston by a screw 12. The plate 11 is provided with an opening 13 through which projects the valve stem 14. Rigidly secured to the piston 8 is

a rack 15 which projects upwardly therefrom as shown in Fig. 1. Cast integral with one side of the head 3 is an inwardly extending projection 16 having therein a vertically extending opening 17 which is preferably rectangular in shape. The inwardly extending projection 16 is also provided with a horizontally extending bore or passageway 18 which communicates with the opening 17 at its inner end. The rack 15 extends through the opening 17 as shown 55 most clearly in Fig. 2 and is guided therein. Journaled in the bore or passageway 18 is a pinion 19 having teeth on its inner end disposed so as to operatively engage the teeth on the rack 15. The outer end of the bore 18 is slightly enlarged and threaded as shown at 20 and the pinion 19 is provided with an annular shoulder 21, the purpose of which will hereinafter appear. Secured to the outer end of the pinion 19 is a crank 22 60 which is non-rotatably secured to the pinion by means of a nut 23. A packing 24 and gland nut 25 is screwed into the outer end of the bore 18 and seals this opening and also holds the pinion 19 in operative engagement with the rack. The packing 24 is 65 held into engagement with the shoulder 21 on the pinion 19 by means of the gland nut 25 and serves to hold the pinion against endwise displacement.

It will thus be seen that the inwardly projecting member 16 constitutes a guide for the piston rack and a journal for the pinion. The advantage of this construction is that it is not necessary to provide oppositely disposed journals in the head and at the same time the rack is always held in operative engagement with the pinion. This construction materially cheapens the device and better adapts it for quantity production 75 at low cost.

If desired, the base member 1 and head 3 may be connected by means of tie rods 26 for the purpose of securely clamping the same to the cylinder 1. However, other 80 means may be adopted for connecting the head and base member to the cylinder. Various changes may be made in the details of my construction without departing from the spirit of my invention and I wish my invention to be limited only in accordance 85 with the scope of the appended claims.

It will now be clear that I have provided

a measuring and dispensing pump which accomplishes the objects of the invention as hereinbefore stated.

Having thus described my invention, what I claim is:

1. A measuring and dispensing pump comprising a hollow base member having a valve therein, a pump cylinder having a valved piston therein, a hollow head having a discharge outlet leading therefrom, means securing said head and base member to the opposite ends of said pump cylinder, said hollow head having a projection on one side thereof, said projection having an axially extending opening extending therethrough and a horizontally extending bore leading from the outside of said hollow head and communicating with said opening at its inner end, a rack connected with said piston and extending through said opening, a pinion journaled in said bore and having its inner end disposed in operative engagement with said rack and means for operating said pinion to reciprocate said piston, said projection constituting a guide for said rack and a bearing for said pinion.

2. A measuring and dispensing pump comprising a pump cylinder having a valved piston therein, a base member secured to the lower end of said pump cylinder, a valved piston working in said cylinder, a head secured to the upper end of said cylinder and having a discharge outlet leading therefrom, said head having an inwardly extending integral projection on one side thereof, said projection having a vertically disposed opening extending therethrough and a horizontally disposed bore or passageway communicating with said opening at its inner end leading to the outside of said head, a piston rack having its lower end secured to said piston and extending upwardly through said opening and guided therein, a pinion journaled in said bore or passageway and having its inner end disposed in operative engagement with said rack, means restricting the lateral movement of said pinion and means for operating said pinion to recipro-

cate said piston, said projection constituting a guide for said piston rack and a bearing for said pinion.

3. A pump of the character described comprising a pump cylinder, a base member secured to the lower end of said pump cylinder, a head secured to the upper end of said pump cylinder and having a discharge outlet leading therefrom, said head having an inwardly extending projection cast integral therewith, said projection having a vertically disposed rectangular opening therein and an annular horizontally disposed bore communicating with said opening at its inner end and leading through said head, a valved piston within said pump cylinder, a rack connected with said piston, said rack being rectangular in cross section and extending through said rectangular opening and guided therein, a pinion journaled in said bore and having its inner end disposed in operative engagement with said rack, means for limiting the end thrust of said pinion and means for operating said pinion to reciprocate said piston, said projection constituting a guide for said rack and holding the same in operative engagement with said pinion, said bore constituting a journal for said pinion.

4. A pump of the class described comprising a pump cylinder, a base member secured to the lower end of said cylinder, a head secured to the upper end of said cylinder and having a discharge outlet leading therefrom, a valved piston working in said cylinder, a guide member projecting from one side of said head and having a vertically extending opening therein, a piston rack connected with said piston at its lower end and projecting upwardly through said opening and guided therein, a pinion journaled in said guide member and disposed in operative relation to said rack, and means for operating said pinion to reciprocate said piston.

In testimony whereof, I hereunto affix my signature.

AUSTIN L. WERTZ.
